UNITED STATES PATENT OFFICE.

LEWIS O. CULVER AND JAMES B. WILLS, OF WEST PITTSSTON, PENNSYLVANIA; SAID
WILLS ASSIGNOR TO SAID CULVER.

TRUCK.

1,340,378.

Specification of Letters Patent. Patented May 18, 1920.

Application filed December 20, 1918. Serial No. 267,730.

To all whom it may concern:

Be it known that we, LEWIS O. CULVER and JAMES B. WILLS, citizens of the United States, residing at West Pittston, in the 5 county of Luzerne and State of Pennsylvania, have invented certain new and useful Improvements in Trucks, of which the following is a specification.

This invention relates to improvements in 10 automobile trucks and more particularly to coal trucks, the primary object being to provide an improved structure whereby the coal may be elevated to be ejected into a chute so that the coal may be readily passed from 15 the truck without interfering with pedestrians who might be passing while the truck is being unloaded.

The invention further aims to provide a 20 truck of this character which will include an elevator arranged to derive its power from the driving shaft of the automobile truck so that the coal may be elevated to any desired height, this height being limited only by the size of the elevator.

25 The invention further aims to provide an automobile truck of this character having its coal compartment arranged to form a coal pocket into which the elevator is placed, the latter being arranged to collapse and be held in inoperative position within the 30 pocket when the elevator is not in use.

35 A further object of the invention is to provide a device of this character which consists of comparatively few parts and is simple in construction, but durable and well adapted to withstand the rough usage to which devices of this character are ordinarily subjected.

40 For a full description of the invention and the advantages and merits thereof, reference is to be had to the following description and accompanying drawings, in which:

45 Figure 1 is a side elevation of the device constructed in accordance with our invention, parts being shown in section.

Fig. 2 is a transverse section taken on the line 2—2 of Fig. 1.

50 Fig. 3 is a section taken on the line 3—3 of Fig. 1.

Fig. 4 is a fragmentary section taken on the line 4—4 of Fig. 2.

55 The chassis of the truck is of ordinary construction but by referring to Fig. 1 it will be noted that the body comprises two separate compartments 1 and 2 with which

the coal is received. These compartments are sufficiently spaced apart to form a relatively wide space between the compartments and this space is utilized as a coal pocket 60 3 shown to advantage in Fig. 2 of the drawing. This coal pocket is constructed so that it has sloping inclined sides 4 and its bottom is curved as shown whereby the coal may be readily removed in a manner which 65 will presently appear. The ends of the compartments 1 and 2 have their end walls provided with openings normally closed by sliding doors 5 each of which is provided with a lift rod 6 connected to a pivoted lever 70 7, the latter having a handle 8 whereby the operator may swing the lever to actuate the lift rod for opening either door for permitting the coal to pass from the compartments into the coal pockets 3. The drive 75 shaft 9 of the automobile is provided with a relatively long sleeve 10 which projects through the pocket 3 near the lower end thereof and this sleeve is provided with a clutch element 11 adapted to be engaged by a clutch 80 element 12 carried by the drive shaft 9 so that when the two clutch elements are in engagement the sleeve 10 will be rotated. An elevator frame is also arranged within the pocket 3 and this frame is constructed 85 so that it will be collapsible as shown. This frame comprises two pairs of pivoted arms 13 and 14, the arms 13 being joined together at their lower ends and pivoted on the shaft as shown in Fig. 1 while the arms 14 are also 90 joined together at their lower ends and pivoted on the sleeve 10. These pairs of arms 13 and 14 are sufficiently spaced apart to form the side bars of the collapsible elevator frame adapted to swing to the position 95 shown by dotted lines in Fig. 2.

The upper ends of the arms 13 and 14 are pivotally connected to the two shafts 15 and 16, each of the arms 13 of one pair being connected to one of the shafts at one end 100 thereof and each of the arms 14 being connected to one of the shafts at the opposite end thereof. Upwardly extending arms 17 and 18, also arranged in pairs are connected at their lower ends to the shafts 15 and 16 at 105 the points at which the upper ends of the lower arms 13 and 14 are connected, the ends of the arms being overlapped as shown to form a neat and efficient connection. The upper ends of the arms 17 and 18 converge 110 and the arms in each pair are connected together and pivotally joined to a central

cross shaft 19. It will be readily seen that this construction provides a frame which may be readily collapsed to assume the position shown by dotted lines in Fig. 2 and which may be raised to operative position by moving the shafts 15 and 16 toward each other. A pair of sprockets is provided on each shaft 15, 16 and 19 and also on the sleeve 10 and endless chains 20 are trained over the sprockets and carry buckets 21, the same being arranged to dump when they reach the top of the conveyer when the latter is in operative position as shown in Fig. 2 of the drawing.

15 Each shaft 15 and 16 has attached thereto, a double link member 22 and each of these members is connected to one of the cables 23 both of which are trained over the pulley 23' and wound about a drum 24. A shaft 25 is suitably mounted on one of the compartments 2 and the drum 24 is fixed on the shaft 25 and the latter is provided with cranks 26 which may be manually actuated for rotating the drum so that a pull will be exerted on the cables whereby the link 22 will draw the shafts 15 and 16 toward each other to the position shown by full lines in Fig. 2 for moving the elevator to operative position.

30 A locking device is employed for maintaining the structure in this position and the same includes the pivoted latch members 27, a pair of which are pivotally mounted as at 28 on each wall of each compartment. 35 The terminals of the latch members are shaped to form hooks 29 adapted to engage the shafts 15 and 16 as shown clearly in Fig. 3 of the drawing. A pair of lifting elements 30 is provided for each pair of 40 latches, each lifting member being pivotally connected to one of the latches as clearly shown in Fig. 3. Each pair of lift members is joined together by a pin 31 upon which is mounted a roller 32. A slideable bar 33 is 45 mounted to slide in supporting members 34 and one of these is provided on each side of the device as shown. Each bar is provided with cam edges 35 over which the roller 32 is adapted to move as the bar is reciprocated. 50 This cam edge on each bar is shaped so that the roller is received in a relatively deep recess when the latches are in locked position and when the bar is reciprocated in either direction, the roller will pass over 55 raised portions which form the cams whereby a pull is exerted on the lift members 30 to raise the latches out of engagement with the shafts 15 and 16 thus unlocking the structure and permitting the frame to collapse.

60 A hopper 37 is secured, through the medium of arms 38, to the upper portion of the frame and this hopper is disposed to receive the coal from the buckets when the 65 latter are dumped at the top of the elevator,

the latter moving in the direction indicated by the arrows in Fig. 2. Since the buckets pass into the bottom of the coal pockets, it will be obvious that the coal will be scooped up from the bottom of the coal pocket and elevated to the required height whereupon it will be dumped into the hopper and the latter has one open end disposed to eject the coal into a conveniently located chute which, of course, will conduct the coal to the point of delivery and which, by virtue of the height of the hopper will be considerably above the sidewalk and therefore will not interfere with the movement of pedestrians. It will be obvious that the arms 13, 14, 17 70 and 18 may be increased in length to make the elevator considerably higher if necessary in this manner the chute may be raised considerably higher.

Near the end of each shaft 15 and 16 is a 85 roller 39 and these rollers are adapted to travel over arcuate trackways 40 which are joined to the compartments 1 and 2 by the supporting members 41 and which have their ends curved upwardly as shown in 90 Fig. 2 to provide seats 43 at the terminals of the trackways for receiving the rollers when the elevator frame is collapsed to the position shown by dotted lines in Fig. 2. This is the position that the device assumes 95 when in operative position and it will be obvious that the entire elevator mechanism may be received within the coal pocket so that it will be inconspicuous and will not require much head room. It will be noted 100 that this arrangement does not occupy much space and does not detract, but very little, from the capacity of the truck for the reason that the coal pocket and the space between the compartments may be filled with 105 the coal while the truck is in transit. This coal, in the coal pocket, of course, will be the first to be removed after which the sliding doors 5 will be opened to permit the coal to pass from the compartments 1 and 2 110 into the coal pockets. The truck may be quickly and readily emptied and will not interfere with traffic.

The foregoing description and accompanying drawing have reference to what 115 might be considered to be the preferred or approved form of our invention. We desire it to be understood that we may make such changes in construction, combination and arrangement of parts, material, dimensions, 120 et cetera as may prove expedient and fall within the scope of the appended claims.

Having thus fully described our invention what we claim as new and desire to secure by Letters Patent, is:-

125 1. A truck comprising a body having spaced apart compartments, a collapsible frame mounted in the space between said compartments and comprising a pair of lower and a pair of upper arms, each arm 130

being pivoted to each of the adjacent arms thereto, a pair of shafts passing through the lower ends of said upper arms and through the upper ends of said lower arms 5 and adapted to move toward and away from each other, means provided for holding said collapsible frame in an elevated position, means provided for lowering and elevating said frame, and conveying means passing 10 around said frame.

2. A truck comprising a body having spaced apart compartments, a collapsible frame mounted in the space between said compartments and comprising a pair of 15 lower and a pair of upper arms, each arm being pivoted to each of the adjacent arms thereto, a pair of shafts passing through the lower ends of said upper arms and through the upper ends of said lower arms and 20 adapted to move toward and away from each other, manually operated means connected to said shafts whereby they may be drawn toward each other to raise the said frame, locking elements mounted on the 25 body and adapted to engage said shafts to releasably maintain them in operative positions, said locking elements comprising a pair of pivoted latch members, the latch members being spaced at their ends to form 30 hooks adapted to engage said shafts, means for releasing said hooks from said shafts and conveying means passing around said frame.

3. A truck comprising a body having spaced apart compartments, a collapsible frame mounted in the space between said compartments and comprising a pair of lower and a pair of upper arms, each arm being pivoted to each of the adjacent arms 35 thereto, a pair of shafts passing through the lower ends of said upper arms and through the upper ends of said lower arms and adapted to move toward and away from each other, locking means provided 40 for engaging said shafts so as to hold said frame in an elevated position, a drum mounted upon a shaft provided between said compartments, cables adapted to be wound around said drum, pulleys provided between 45 said shafts, said cables passing around said pulleys and engaging said shafts, means for rotating said drum whereby said collapsible frame may be lowered or elevated and conveying means passing around said frame. 50

4. A truck comprising a body having spaced apart compartments, a collapsible frame mounted in the space between said compartments and comprising a pair of lower and a pair of upper arms, each arm being pivoted to each of the adjacent arms thereto, a pair of shafts passing through the lower ends of said upper arms and through the upper ends of said lower arms and adapted to move forward and away from each other, a drum mounted upon a shaft 60 provided between said compartments, pulleys provided between said shafts, cables provided upon said drum, said cables adapted to pass around said drum and said pulleys, said cables fixedly attached to said first 65 mentioned shafts for operating same when said drum is rotated, whereby the same may be elevated or lowered, a locking element pivotally mounted upon the body, said locking element comprising pivoted latch members, said latch members being spaced at their ends so as to form hooks, said hooks 70 adapted to engage said shafts so as to hold same in an elevated position, means for releasing said locking elements from said 75 shaft and conveying means passing around said frame.

5. A truck comprising a body having spaced apart compartments, a collapsible frame mounted in the space between said compartments and comprising a pair of lower and a pair of upper arms, each arm being pivoted to each of the adjacent arms thereto, a pair of shafts passing through the lower ends of said upper arms and through the upper ends of said lower arms and adapted to move toward and away from each other, means provided for holding said collapsible frame in an elevated position, and means provided for lowering and elevating said frame, sprocket wheels provided at the conjunction of said arms, an endless chain adapted to train on said sprocket wheels, and a carrying means provided upon said chain. 85 90 95 100

In testimony whereof we affix our signatures in presence of two witnesses.
